UNITED STATES PATENT OFFICE

ADOLPH M. AUGSTEIN AND AUGUST EGERER, OF GREAT NECK, NEW YORK

DESIGN FOR A KNITTED SWEATER

Application filed June 23, 1928. Serial No. 27,250. Term of patent 3½ years.

To all whom it may concern:

Be it known that we, ADOLPH M. AUGSTEIN and AUGUST EGERER, citizens of the United States of America, and residents of Great Neck, Long Island, county of Nassau, State of New York, have invented a new, original, and ornamental Design for a Knitted Sweater, of which the following description in connection with the accompanying drawing is a specification.

The single figure of the drawing is a front view of a knitted sweater with the sleeves folded toward the front showing our new design which resides specifically in the detailed design shown about the sleeves and waistband of the sweater.

We claim as our invention:

The ornamental design for a knitted sweater, substantially as shown and described.

ADOLPH M. AUGSTEIN.
AUGUST EGERER.
